UNITED STATES PATENT OFFICE.

DUDLEY FREEMAN, OF ROXBURY, MASSACHUSETTS.

GARMENT.

1,421,446.

Specification of Letters Patent.

Patented July 4, 1922.

Application filed July 23, 1921. Serial No. 486,950.

To all whom it may concern:

Be it known that I, DUDLEY FREEMAN, a citizen of the United States, and resident of Roxbury, county of Suffolk, State of Massachusetts, have invented an Improvement in Garments, of which the following description, in connection with the accompanying drawing, is a specification, like characters on the drawing representing like parts.

10 This invention relates to a garment which may be used for various purposes, either as an under or as an outer garment. It is particularly designed, however, in some of the forms illustrated as an over-garment in the 15 nature of a working suit or overalls and in another form illustrated for a diaper or drawers.

The object of the invention is to provide a garment which may be placed over the 20 obverse face, either the front or back, of the person and secured in position by flaps extending around the reverse portion of the person and connected by separable fasteners.

The object of the invention is to provide 25 a garment of this character which may be quickly placed upon the wearer and removed therefrom and in which the fastening devices are all readily accessible.

These and other objects and features of 30 the invention will appear more fully from the accompanying description and drawings and will be particularly pointed out in the claims.

In the drawings:

35 Fig. 1 is a front elevation of a preferred form of the garment as it appears on the wearer, with one leg flap shown extended in dot and dash lines;

40 Fig. 2 is a rear elevation of the construction shown in Fig. 1, with one side of the seat flap shown extended in dot and dash lines;

45 Fig. 3 is a front elevation of the upper portion of another form of garment embodying the invention;

Fig. 4 is a front elevation of the upper portion of a third form of garment embodying the invention; and,

50 Fig. 5 is a front elevation of a fourth form of garment embodying the invention.

The garment of this invention may be utilized for a wide range of purposes, as already noted, and may be worn either as an under garment or as an outer garment 55 and, as examples of the range of forms it may take, it is shown both as designed for

use as an outer garment such as a wrapper or working suit or overalls and as an under garment such as a pair of drawers or diaper. It may be made of any suitable material and 60 varied in shape and size according to the person and the use for which it is intended.

Various constructions embodying the main and characteristic features of the invention are illustrated for the purpose of showing 65 something of the variations which may be made in the garment apart from its essential features.

The invention provides a garment which may be readily placed upon the person of 70 the wearer and removed therefrom in a simple and expeditious manner. This is particularly desirable in many cases, as for example in the forms illustrated, viz, in working suits or union overalls carried by 75 automobilists or in drawers or diapers and which it is desired to don and remove quickly. The invention also provides a garment in which the parts are secured in place by separable fasteners, such as, the ordinary 80 snap fasteners, all of which are readily accessible at one face and preferably at the front of the person. This enables the garment to be secured in place and unfastened when the movements of the wearer are hampered by clothing, or by any other reason.

The separable fasteners illustrated diagrammatically at various points in the garment may be of any suitable construction such as commonly employed in garments, 90 either buttons and button-holes, snap fasteners, or other familiar devices.

Referring first to the construction illustrated in Figs. 1 and 2, the garment comprises an obverse trunk section, which in 95 this case is a front trunk section 1, which essentially covers the lower portion of the torso and which, in the form illustrated, also extends upwardly covering the entire front of the torso. This front trunk section 100 may be provided with suitable pockets 2 and if desired with a fly 3. It is shaped to fit the person and in the form illustrated is provided with a central longitudinal seam 4. When this front trunk section extends 105 up over the chest, as in the form illustrated, it may also be provided with breast pockets 5 and if desired with a collar 6.

Leg flaps 7 depend in this form from and are connected to the front trunk section. 110 These leg flaps preferably are integral with and form a downward continuation of the

front trunk section 1. Gores 8 may be provided to assist in giving the proper shape. These leg flaps preferably cover the entire fronts and preferably extend to the bottom 5 of the legs. Side extensions 9 are connected to the outer edge of each leg flap and are of sufficient size to wrap around the legs and at their lower portions 10 come around to the front of the legs at the bottom. Separable fasteners 11 are provided on the portions 10 of the extensions 9 and on the underlying portions of the leg flaps 7.

A reverse section and in this case seat flap 12, shaped to cover the reverse lower 15 portion of the torso or in this case the seat and upper rear portions of the legs of the person, is connected to the inner edges of the leg flaps 7 preferably by lines of stitching 13. This seat flap is properly shaped 20 and for that purpose gores 14 may be employed. The seat flap may also be provided with suitable rear pockets 15. This seat flap extends up, preferably somewhat above, the waist line as indicated and is extended at 25 its upper outer corners 16 sufficiently to come around to the front and lap under the front section 1. Separable fasteners 17 are provided on the upper outer corners 16 of the seat flap and the overlying portion of the 30 front trunk section 1 whereby these parts are connected.

The reverse section or seat flap together with the leg flaps thus together surround and cover the legs and the separable fastening means act to secure together and hold in position these parts upon the legs.

A back flap is secured to the front trunk section in this case and adapted to pass around the back and over the shoulders and 40 is secured in place at the front to the front trunk section. In the form illustrated this back flap 18 is a continuation of the chest portion of the front trunk section 1, passes over the left shoulder, covers the major portion 45 of the back and at its lower corner 19 passes over the front trunk section 1 near the waist line and is connected by a separable fastener 20 with the front trunk section. In this form the right shoulder is 50 covered by an additional flap 21 connected to the chest portion of the front trunk section 1 and the back flap 18 may be secured thereto at the back of the neck, especially when using the collar 6, by a separable fastener 35.

Sleeves 22 may be provided and permanently or detachably secured to the garment. As illustrated these sleeves are detachably secured by separable fasteners 23.

60 When the garment of this form is to be put on all the separable fasteners are disconnected and the various flaps opened up. The wearer, holding the garment in front of him, places his arms through the sleeves 65 22 if they are used, or if not through the

arm hole sections, and then seizes the lower corner 19 of the back flap 18, passes it around his back and fastens the separable fastener 35, when employed, and also fastens the separable fastener 20 at the front. He 70 then reaches between his legs and throws up the seat flap, which is then hanging down, until it covers the rear portion of his legs and seat and then brings the upper outer corners 16 to the front under the front trunk 75 section 1 and fastens the separable fasteners 17. He then takes the side extensions 9 successively and wraps them about the rear of his legs bringing the lower outer corners 10 around the inside of the leg and to the 80 front and fastens the separable fasteners 11. The whole operation is quickly and expeditiously performed and the garment when in place covers the entire person. To remove the garment the various separable fasteners 85 are unfastened and the entire garment is pushed off at the front. While the provision of the extensions of the leg flaps are desirable the important feature is that the leg flaps as a whole, together with the seat 90 flap act to surround and cover the legs and the separable fastening means act to secure these flaps together in position on the legs.

The construction shown in Fig. 3 varies from that already described only in the 95 upper portion of the garment and is to be utilized where it is only necessary to provide a bib or covering for the chest. In this construction the front trunk section 24 is extended upwardly covering the chest at 25 100 and is provided at the left shoulder with a back flap 26 connected thereto. This back flap passes over the left shoulder, around the back, over the right shoulder and down in front where it is secured to the front trunk 105 section by a separable fastener 27.

Fig. 4 illustrates still another form which the upper portion of the garment may take. In this case the back flap is an upward extension of the seat flap, passes over both the 110 shoulders, an opening being left at 28 for the neck, and passes down over and covers the chest at 29. At its lower portion it is connected to the front section 30 by separable fasteners 31. This flap at the front 115 may also be provided with suitable pockets 32 and sleeves may be employed if desired, the sleeves 33 illustrated being detachably secured to the garment by separable fasteners 34.

The entire garment, in the forms illustrated in Figs. 1 to 4 in each case as will be seen, is put on much in the same manner as an apron and is removed in the same manner. That is, the garment is held in front of the wearer and is put on by bringing the various extensions and flaps around the body and legs and securing it in place. This also eliminates the objection to putting the feet and legs through closed legs, such as those 130

of the ordinary overalls or similar garments, because there is no danger of soiling the interior of the garment as the feet are passed through it and then bringing the 5 soiled portion in contact with the clothing of the wearer.

Fig. 5 illustrates a slightly different form 10 of garment also embodying the invention and designed for use as a pair of drawers or diaper or similar garment. In its general construction it is a reversal of the forms already described. In this case the garment is designed to be put on over the back of the 15 person and the various flaps and extensions are arranged to cover the front of the person and to be secured in place preferably by separable fasteners at the front.

In this case the garment comprises an obverse 20 trunk section in the form of a back section 36 which essentially covers the lower portion of the torso or seat. Short leg flaps depend from and form a downward continuation of this section. Side extensions 37, 25 one of which is shown in extended position by dot and dash lines at the right, are connected to, and preferably integral with, the outer edge of each leg flap and are of sufficient size to wrap around the leg fronts. A reverse trunk section, in this case a front flap 30 38, shaped to cover the front lower portion of the torso and upper front portions of the legs, is connected to the inner edges of the leg flaps preferably by lines of stitching 39. The side extensions 37 are secured to the 35 front flap at its upper outer and lower inner corners by suitable separable fasteners 40 and 41 so that the side extensions overlap the front flap and therewith cover the front portion of the person.

40 When this form of garment is to be put on, it is placed against the back of the person, the front flap is thrown up between the legs over the front, and the side extensions are brought around the front and fastened in 45 place. To remove it, the operation is reversed.

Having thus described my invention, what I claim as new, and desire to secure by Letters Patent, is:

50 1. A garment comprising an obverse trunk section, depending leg flaps connected to the obverse trunk section to cover the obverse portions of the legs, a reverse flap connected to the inner edges of the leg flaps to cover 55 the reverse portion of the trunk, separable fastening means for securing the upper outer corners of the obverse trunk section and reverse flap together, a side extension connected to the outer edge of each leg flap, the said extensions acting, when wrapped around the 60 legs to cover with the reverse flap the reverse portions of the legs, and separable fastening means for securing the lower outer corner of each extension in position.

2. A garment comprising a front trunk 65 section, depending leg flaps connected to the front trunk section to cover the leg fronts, a seat flap connected to the inner edges of the leg flaps to cover the seat, separable fastening means for securing the upper outer 70 corners of the seat flap to the front trunk section, a side extension connected to the outer edge of each leg flap, the said extensions acting, when wrapped around the legs, to cover with the seat flap the leg backs, and 75 separable fastening means for securing the lower outer corner of each extension in position.

3. A garment comprising the construction defined in claim 2, together with a back flap 80 secured to the front trunk section to pass around the back and over at least one of the shoulders and separable fastening means for securing the free end of the back flap to the front trunk section. 85

4. A garment comprising the construction defined in claim 2, together with a flap extending over the back and at least one of the shoulders, and separable means for securing the said flap to the front trunk section. 90

5. A garment comprising the construction defined in claim 2, in which the front trunk section is extended to cover the chest and one shoulder and an adjacent portion of the back, together with a back flap connected to the 95 side of the front trunk section and covering the other shoulder and an adjacent portion of the back, and separable fastening means for securing the free end of the back flap to the front trunk section. 100

6. A garment comprising an obverse trunk section, depending leg flaps connected to the obverse trunk section to cover the obverse portions of the legs, a reverse flap connected to the inner edges of the leg flaps to cover 105 the reverse portion of the trunk, separable fastening means for securing the upper outer corners of the obverse trunk section and reverse flap together, the reverse flap and the leg flaps together acting to surround and 110 cover the legs, and separable fastening means for securing the reverse flap and leg flaps together in position on the legs.

7. A garment comprising a front trunk section, depending leg flaps connected to the 115 front trunk section to cover the leg fronts, a seat flap connected to the inner edges of the leg flaps to cover the seat, separable fastening means for securing the upper outer corners of the seat flap to the front trunk 120 section, the seat flap and the leg flaps together acting to surround and cover the legs, and separable fastening means for securing the seat flap and leg flaps together in position on the legs. 125

In testimony whereof, I have signed my name to this specification.

DUDLEY FREEMAN.
